ROLLER RAIL FOR HEAT TREATING FURNACES

Filed Feb. 8, 1928

Patented Dec. 4, 1928.

1,693,870

UNITED STATES PATENT OFFICE.

JOSEPH SAMMON, OF KEARNY, NEW JERSEY, ASSIGNOR TO DRIVER-HARRIS COMPANY, OF HARRISON, NEW JERSEY, A CORPORATION OF NEW JERSEY.

ROLLER RAIL FOR HEAT-TREATING FURNACES.

Application filed February 8, 1928. Serial No. 252,930.

My invention relates to improvements in roller rails for conveying carburizing boxes and the like through heat treating furnaces and has for its object to produce a roller rail 5 whose base is not liable to be distorted by the heat of a furnace.

Heretofore roller rails have been made of heat resisting alloys, the same comprising a flat bottom U-shaped base composed of a bottom 10 and two side members which have recesses in their upper edges and rollers supported by said recesses. These channel-like supports, however, become distorted by the heat. They become warped and change their 15 shape to such a degree as to throw the bearing recesses out of alinement which interferes with the action of the rollers and with the free passage of boxes upon the rollers. I have discovered that if the roller supporting side 20 member is connected by portions integral therewith which are located adjacent to the lower edges of the sides at points beneath the rollers and are spaced away from said lower edge so as to be located at points adjacent to 25 the upper edges of the sides at points between said recesses, the objectionable distortion is largely reduced and practically eliminated.

The following is a description of an embodiment of my invention reference being 30 had to the accompanying drawings, in which:

Figure 1 is a side elevation of a roller rail embodying my invention;

Fig. 2 is a portion of the same on an enlarged scale;

Fig. 3 is a section on the line 3-3, Fig. 2;

Fig. 4 is a section on the line 4-4, Fig. 2, and

Fig. 5 is a plan view of a clamp for holding two sections together.

Referring more particularly to the drawings, 2 and 4 are the side members of a base provided at their upper edges with alining bearing recesses 6 for trunnions 8 of rollers having central enlargements 10. The peripheral surfaces of these enlargements are spherical and preferably have a radius of about two inches. The side members are connected together at points 12 beneath the rollers by portions integral with said side members, and at 45 points 14 between the recesses and adjacent to the upper edges of the side members and spaced away from the lower edges by other portions integral with said side members. Preferably the connecting portions are continuous with one another so as to form an 50

undulating web throughout the length of the base.

With my construction the upper edges of the rail are held at a fixed distance from one another by the connections at 14 between the 60 recesses, and the lower edges of the side portions of the rail are held in fixed distance from one another by the portions at 12 beneath the recesses.

In practice both the support and rollers 65 are made of a heat resisting alloy so as to withstand the intense heat of the heat treating furnace.

The support rests upon the floor 16 of the furnace and may be composed of sections held 70 together by clamps 18 embracing ears 20 on the adjacent ends of the sections and bolts 22 which pass through both the clamps and the ears.

The receiving end of the roller rail is provided with a depending portion 24 anchoring the rail to the furnace bottom against thrust due to shoving the boxes toward the delivery end.

26 is a skid rail at the delivery end of the 80 roller rail.

As will be evident to those skilled in the art, my invention permits various modifications without departing from the spirit thereof or the scope of the appended claims. 85

What I claim is:

1. A roller rail for heat treating furnaces consisting of two side members having at their upper edges alining bearing recesses and portions integral with said side members connecting said side members together at points adjacent to their lower edges and beneath said bearing recesses and at points spaced away from said lower edges and between said recesses, and rollers in said recesses. 90

2. A roller rail for heat treating furnaces consisting of two side members having at their upper edges alining bearing recesses and portions integral with said side members connecting said side members together at points adjacent to their lower edges and beneath said bearing recesses and at points spaced away from said lower edges and adjacent to said upper edges between said recesses, and rollers in said recesses. 100

3. A roller rail for heat treating furnaces consisting of two side members having at their upper edges alining bearing recesses and portions integral with said side members connecting said side members together at points 110

adjacent to their lower edges and beneath said bearing recesses and at points spaced away from said lower edges and between said recesses, and rollers in said recesses, said connecting portions being continuous so as to form a web.

4. A roller rail for heat treating furnaces consisting of two side members having at their upper edges alining bearing recesses and 10 portions integral with said side members connecting said side members together at points

adjacent to their lower edges and beneath said bearing recesses and at points spaced away from said lower edges and adjacent to said upper edges between said recesses, and rollers 15 in said recesses, said connecting portions being continuous so as to form a web.

In testimony whereof, I have signed my name to this specification this 3rd day of February, 1928.

JOSEPH SAMMON.
